[57] CLAIM

The ornamental design for a conical double end cap for use with a cable splice case, substantially as shown and described.

DESCRIPTION

FIG. 1 is a top plan view of the conical double end cap for use with a cable splice case showing our new design; FIG. 2 is a front elevational view of said conical double end cap, the rear elevational view being a mirror image thereof;

FIG. 3 is a right side elevational view of said conical double end cap, the left side being a mirror image thereof; and

FIG. 4 is a bottom plan view of said conical double end cap.
